UNITED STATES PATENT OFFICE.

PAUL BATEMAN, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CARRY-IRON.

1,078,244.

Specification of Letters Patent.

Patented Nov. 11, 1913.

Application filed December 26, 1912. Serial No. 738,696.

To all whom it may concern:

Be it known that I, PAUL BATEMAN, residing at St. Louis, Missouri, and being a citizen of the United States, have invented certain new and useful Improvements in Carry-Irons, (Case B,) of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a front elevational view of a coupling support, showing the coupler in section, and showing in dot and dash lines the carry iron in dropped position. Fig. 2 is a plan view of the underside of the device shown in Fig. 1, and Fig. 3 is a transverse vertical sectional view through a slightly modified device similar to the one shown in Figs. 1 and 2, and taken on a plane indicated by the line 3—3 of Fig. 2, showing a modified carry iron in three positions.

My invention relates in general to a draw-bar coupling support, and more particularly relates to a removable carry iron and its supporting buffer casting or dead block.

My invention has for its object to provide an improved carry iron arrangement, in which the iron may be dropped to a position without becoming detached from the supporting parts, in order to permit the vertical lowering of the coupler and its attached mechanism.

It is a further object to provide in a device of the above outlined character relatively broad flat bearing surfaces for the iron, and to so arrange the parts that the iron may be locked into position in a simple manner, and without multiplicity of structural parts.

I attain the above outlined objects, broadly, by providing a dead block having aligned supporting shelves carrying a hooked end carry iron, the hook of which is adapted to engage a stop when in dropped position, so as to maintain the iron in position on the block.

Described more in detail I have shown a 55 suitable ribbed face plate 4, adapted to be fastened by means of rivets 5 to the end sill or other suitable part of the car, extending forwardly from the lower central portion of which plate and formed integral therewith 60 is the open bottom hood 6, adapted to contain the coupler 7. Each wall of the hood is formed into an outstanding foot 8, the bottom of which feet are formed by means of shelves 9 and 10. Paralleling the shelf 65 10 and positioned a short distance above the same is the overhanging ledge 11, forming with the shelf 10 a pocket for one end of the carry iron 12, hereinafter more fully described.

The shelf 9 is preferably not of the full width of the foot 8, but is outlined transversely by open-ended passages 3 and 13. The inner wall 14 forming a portion of that side of the hood 6 including the shelf 9 has 75 an opening 15 extending therethrough and terminates a distance above the shelf 9 to permit the positioning of the carry iron between the shelf and lower end of the wall.

The carry iron 12, as shown in Fig. 1, is 80 a flat bar having an opening extending through one end thereof, the opposite end of which is bent into a laterally extending finger or head 16 to form a hooked end to the iron, and in Fig. 3 a slightly modified 85 form is disclosed, in that two fingers may extend from its end transversely of the iron to form the T-head 17, shown.

It will be understood that the iron 12 is inserted from the left-hand side of the 90 block shown in Fig 1 until it rests upon the shelves 9 and 10 and between the shelves, the wall 14 and ledge 11, in which position it is locked by means of the pin 18 passing through the ledge 11, the aperture in the iron 12 and through the shelf 10, in which position it is locked by means of the cotter 19. Where the T-shaped head is used, as shown in Fig. 3, one portion of the head will engage the shelf 9, so as to restrain movement of the iron in one transverse direction.

To dismount the iron it is merely necessary to withdraw the same from its seat or shelf 10, permitting the iron to fall into the dot and dash position shown in Fig. 1, the 105 finger or head 16 extending into the opening 15, the lower edge of which opening may be reinforced by a thickened strength-

ening portion 21, if this should be found necessary.

The iron when swung into its dropped position swings on the corner 22 of the shelf 9, and it is possible that the rough under-surface of the iron 12, characterizing these commercially formed members, will prevent the iron 12 dropping so low that the finger 16 will not be positioned within the opening 15, but, if found necessary, a groove 23 or teeth may be placed in the underside of the iron so as to form a groove to contain the edge 22, thereby forming a stationary pivoting point for the iron 12 until the finger 16 is in position to drop into the opening 15 in which position the hooked end of the iron engages the thickened portion 21.

Particularly noting the form of carry iron shown in Fig. 3, it is seen that each end of the iron has a relatively broad bearing portion 24, that the central portion between the bearing portions 24 has an offset 25, so that by reversing the position of the iron the offset portion may be varied relative to the seats 9 and 10, so as to vary the position of the coupler 7 vertically. In this figure it will be noted that the angled face 26 will perform the functions claimed for the groove 23, permitting the iron to fall into almost a vertical position so as to bring the head 17 into the opening 15 before the falling iron brings its head on to the thickened bottom edge 21 of the opening.

What I claim is:

- 35 1. The combination with a coupler, of a dead block having alined shelves, a carry iron having a laterally projecting head said carry iron resting directly on and being supported in coupler-carrying position solely by said shelves, and means formed on the dead block adapted to engage the head to maintain the iron connected with the block when the iron is dropped away from said coupler.
- 45 2. The combination with spaced supports forming a coupler space therebetween, a coupler positioned in said space, a carry iron pivoted to one of said supports, and in one position resting on both of said supports to carry the coupler and adapted to be withdrawn longitudinally of said carry

iron from one of said supports to swing away from said coupler.

3. The combination with spaced supports, a carry iron supported by and adapted in one position to bridge the space between said supports, said carry iron being provided with a notch intermediate its end portions adapted to retard sliding movement of said carry iron when dropping into inoperative position.

4. A carry iron having a body portion terminating in a hooked end adapted to act as a support when the iron is in a dropped position in combination with a dead block having a shoulder adapted to engage said hooked end in said dropped position.

5. The combination with a supporting shelf, of a carry iron slidable horizontally on said shelf and adapted to rock thereon to inoperative position, said bar having a means on the underside thereof adapted to be engaged by the shelf to retard sliding movement of said bar.

6. A dead block having opposed walls with openings therethrough, a carry iron supporting shelf, a stop disposed above said shelf, and a hooked end carry iron adapted to be supported on said shelf and adapted to drop from a horizontal position and when in dropped position to have the hooked end engage said stop in one of said openings and support the iron in the dropped position.

7. The combination with spaced supports, a carry iron supported in horizontal position by and adapted to bridge the space between said supports, said carry iron being adapted to move longitudinally in a horizontal position and to drop from a horizontal position to an inoperative position, and a notch in the carry iron intermediate its ends adapted to retard its sliding movement when dropping to said inoperative position.

In witness whereof I have hereunto set my hand in the presence of two witnesses.

PAUL BATEMAN.
